United States Patent Office

Des. 230,665
Patented Mar. 12, 1974

230,665

NEEDLEPOINT CANVAS

Marcia Podell, 233 E. 69th St.,
New York, N.Y. 10021

Filed July 8, 1971, Ser. No. 160,979

Term of patent 3½ years

Int. Cl. D6—13

U.S. Cl. D3—9 D

FIG. 1

FIG. 2

FIG. 1 is a top plan view of a needlepoint canvas showing my new design. FIG. 2 is a top plan view of a second embodiment thereof, wherein contrast has been indicated.

I claim:

The ornamental design for a needlepoint canvas, as shown.
